US00D974139S

(12) **United States Design Patent** (10) **Patent No.:** **US D974,139 S**
(45) **Date of Patent:** **** Jan. 3, 2023**

(54) **BASE FOR SUPPORTING ROUTER BITS**

(71) Applicant: **Woodpeckers, LLC**, Strongsville, OH (US)

(72) Inventor: **Mark Robert Heath, Jr.**, Strongsville, OH (US)

(73) Assignee: **WOODPECKERS, LLC**, Strongsville, OH (US)

(**) Term: **15 Years**

(21) Appl. No.: **29/824,451**

(22) Filed: **Jan. 25, 2022**

(51) LOC (14) Cl. **08-05**

(52) U.S. Cl.

USPC **D8/71**

(58) **Field of Classification Search**

USPC D15/131, 132, 140, 143; D8/71, 499; D3/315

CPC B25H 3/003; B25H 3/04

See application file for complete search history.

(57) **CLAIM**

The ornamental design for a base for supporting router bits, as shown and described.

DESCRIPTION

FIG. 1 is a top front right side perspective view of the base for supporting router bits in accordance with my design; FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom elevation view thereof; and,

FIG. 8 is another top front right side perspective view thereof. The broken lines illustrate portions of the base for supporting router bits which form no part of the claimed design.

1 Claim, 6 Drawing Sheets
